GRADUATED HAIRCUTTING COMB

William S. Hendra, New Bedford, Mass.

Application January 13, 1950, Serial No. 138,435

4 Claims. (Cl. 132—45)

1

This invention relates to combs for cutting hair particularly by amateurs, and in particular a comb having a handle extended therefrom with a plurality of spacing fingers extended through the comb and adapted to be adjusted for cutting hair to different lengths.

The purpose of this invention is to provide adjustable means in combination with a comb whereby an amateur may cut hair evenly and with the length of the hair graduated from the neck to the upper part of the head.

Various attachments and devices have been provided in combination with combs for varying the distance the comb may be held from the head to facilitate cutting hair but it has been found difficult to regulate the device for cutting hair accurately to different lengths as cutting progresses upwardly on the head. With this thought in mind this invention contemplates a comb having means for positively setting fingers extended from the comb to different positions and in which the position of the fingers is adjusted continuously as the comb is in use.

The object of this invention is, therefore, to provide means for mounting spacing fingers on a comb for cutting hair whereby the distance of the spacing fingers from the comb is readily adjustable.

Another object of the invention is to provide means for adjustably mounting spacing fingers on a comb for cutting hair in which the fingers are brought against the comb as the comb is inserted in the hair and then released for cutting.

A further object of the invention is to provide an improved comb for cutting hair to different lengths having spacing fingers adjustably mounted thereon which is of a comparatively simple and economical construction.

With these and other objects and advantages in view the invention embodies a comb having a handle extended at a right angle from the back thereof with a bar having a plurality of spacing fingers thereon extended through the comb and adjustably mounted on the handle and wherein the position of the bar is controlled by a trigger and spring.

Other features and advantages of the invention will appear from the following description taken in connection with the drawings wherein:

Figure 1 is a cross section through the improved hair cutting comb taken on line 1—1 of Figure 2.

Figure 2 is a plan view of the comb shown in Figure 1.

2

Figure 3 is a detail showing a section on line 3—3 of Figure 1 showing the intermediate part of the comb with the ends broken away.

Figure 4 is a detail showing a section on line 4—4 of Figure 2.

Figure 5 is a detail showing a section taken on line 5—5 of Figure 1.

Figure 6 is a similar detail taken on line 6—6 of Figure 1.

Referring now to the drawings wherein like reference characters denote corresponding parts the hair cutting comb of this invention includes a comb 10, a handle 11, a plurality of spacing fingers 12 carried by a bar 13 and a trigger 14 carried by a tube 15 on a stem 16 having a knurled head 17 on the outer end.

The comb 10 is provided with a back 18 and a plate 19, having a slot 20 therein, extends from the center of the back 18 and is positioned perpendicular to the plane of the comb. The handle 11 is carried by the outer end of the plate 19 and the plate 19 is also provided with a slot 21 through which the knurled nut 17 extends and a bearing 22 in which the outer end of the stem is journaled.

The stem 16 extends from the bearing 22 through an opening 23 in the back 18 of the comb 10 and a head 24 is provided on the end of the stem and positioned on the opposite side of the comb, as shown in Figure 1.

A stop plate 25 is threaded on the stem 16 and this plate, which is provided with a flat surface 26 that engages the upper surface of the plate 19 to prevent rotation thereof, provides a stop to limit outward movement of the bar 13 on which the spacing fingers 12 are carried. The spacing fingers 12, which are L-shaped as shown in Figure 4, are provided with shanks which extend through openings 27 in the back of the comb and as the bar 13 is actuated by the trigger 14 the fingers 12 are drawn against the outer surface of the comb 10. The tube 15 on which the trigger 14 is carried is integral with the bar 13 and is also provided with a flange 28 on the inner end. The flange 28 is provided with a pointer 29 that is positioned to travel on a scale 30 whereby the stop plate 25 may be positioned to regulate the length of hair being cut. The bar 13 and spring fingers 12 are urged outwardly by a spring 31 positioned on the stem 16.

The back of the comb is also provided with a cover plate 32 that is secured to the comb by screws 33, thereby providing a shield to prevent hair dropping into the moving parts of the device.

With the parts arranged in this manner the

spacing fingers 12 may first be set by the knurled head 17 so that they are $\frac{1}{16}$ of an inch from the comb 10 and when the comb is placed against the head the fingers 12 are held against the outer surface of the comb by the trigger 14. When the comb is in position the trigger is released and the spring 31 forces the spacing fingers 12 away from the comb and the hair is cut against the inner surface of the comb.

In the next step the spacing fingers are set to $\frac{1}{8}$ of an inch and the fingers are drawn against the comb and released in the same manner. This cycle of operations continues as cutting progresses upwardly on the head and the hair may, therefore, be cut evenly and with the length of the hair increasing toward the upper part of the head.

It will be understood that modifications may be made in the design and arrangement of the parts without departing from the spirit of the invention.

What is claimed is:

1. In a hair cutting device, the combination which comprises a comb having teeth extended from a back, a handle extended from the back of the comb, spacing fingers positioned in a plane parallel to the comb and carried by shanks extended through the back of the comb, a bar carried by the inner ends of the shanks of the spacing fingers and spaced from the back of the comb, a stop plate slidably mounted on the handle and positioned to be engaged by said bar for limiting outward movement of said spacing fingers, a stem mounted on the handle and threaded in the said stop plate for regulating the bar inwardly to draw the fingers against the comb, and a spring on the stem for resiliently urging the bar toward the comb with the fingers spaced from the comb.

2. In a hair cutting device, the combination which comprises a comb having teeth extended from a back, a handle extended from the back of the comb, spacing fingers positioned in a plane parallel to the comb and carried by shanks extended through the back of the comb, a bar carried by the inner ends of the shanks of the spacing fingers and spaced from the back of the comb, a stop plate slidably mounted on the handle and positioned to be engaged by said bar for limiting outward movement of said spacing fingers, a stem mounted on the handle and threaded in the said stop plate for regulating the bar inwardly to draw the fingers against the

comb, and means resiliently urging the bar toward the comb and the fingers away from the comb.

3. In a hair cutting comb, the combination which comprises an elongated back having teeth extended from one edge providing a comb, a handle extended from one side of the back, a stem having threads thereon and having a knurled head on the outer end journaled in the back and also on the handle, a tube slidably mounted on the stem, a trigger carried by the tube, a spring resiliently urging the tube toward the back with the teeth extended therefrom, and a bar carried by the tube and having spacing fingers thereon extended through the back of the comb and having extended ends positioned in a plane parallel to the plane of the comb whereby the spacing fingers are drawn against the comb by the trigger and urged away from the comb by the spring.

4. In a hair cutting comb, the combination which comprises an elongated back having teeth extended from one edge providing a comb, a handle extended from one side of the back, a stem having threads thereon and having a knurled head on the outer end journaled in the back and also on the handle, a tube slidably mounted on the stem, a trigger carried by the tube, a spring resiliently urging the tube toward the back with the teeth extended therefrom, a bar carried by the tube, having spacing fingers thereon extended through the back of the comb and having extended ends positioned in a plane parallel to the plane of the comb whereby the spacing fingers are drawn against the comb by the trigger and urged away from the comb by the spring, a stop plate threaded on the stem, and a cover plate extended from the back of the comb and positioned over the bar on which the spacing fingers are carried.
